Primary Examiner — Anhdao Doan(74) *Attorney, Agent, or Firm* — Invenstone Patent, LLC(57) **CLAIM**

The ornamental design for a portable electronic device, as shown and described.

DESCRIPTION

FIG. 1 is a perspective view of a portable electronic device showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a view illustrating a state in which the claimed design is connected to a portable terminal.

The broken lines in FIG. 3 illustrate portions of the portable electronic device that form no part of the claimed design. In FIG. 8, the broken lines depicting a portable terminal represent environmental subject matter and form no part of the claimed design.
